UNITED STATES PATENT OFFICE.

JOHN R. REED, OF WESTFIELD, MASSACHUSETTS.

DESIGN FOR A RADIATOR.

SPECIFICATION forming part of Design No. 20,574, dated March 10, 1891.

Application filed December 9, 1890. Serial No. 374,085. Term of patent 14 years.

To all whom it may concern:

Be it known that I, JOHN R. REED, a citizen of the United States, residing at Westfield, in the county of Hampden, in the State of Massachusetts, have invented and produced a new and original Design for Radiators, of which the following is a specification, reference being made to the accompanying drawings, forming part thereof.

10 Figure 1 is a side elevation of a radiator embodying my novel design; Fig. 2, an elevation of one of the pipes or loops thereof.

In the production of the design for radiators herein shown my aim has been to improve 15 the general ornamental appearance of the radiator, which I have done by breaking up all continuous or regular rectangular lines or bands forming the ornamentation, and in place of such lines I have made use of ornamentation more irregular or wavy, and consequently more pleasing to the eye.

In the drawings each loop or pipe A B C, &c., is shown as composed of two or more legs communicating with a head a and with a base 25 e . The head part of each loop or pipe is ornamented at its ends to leave ears a' a'' of unequal length, thus forming cusps, which, when the loops or pipes are reversely assembled in a radiator, as shown in the drawings, 30 extend downwardly for unequal distances

upon the legs, or terminate on the legs at unequal distances from the top of the head, the upper end of the radiator thus presenting to the eye a denticulated appearance, as in Fig. 1, where the foliated cusps terminate in different horizontal planes. The base e of each loop or leg of the radiator is also ornamented to present the appearance of pedestals e' e'' of different lengths, which, when the pipes are reversely assembled in a radiator, as shown in 40 the drawings, Fig. 1, extend upwardly along the side of the radiator for unequal lengths or terminate in different horizontal planes.

The essential leading feature of my design consists in the ornamentation of the heads of 45 the loop-pipes, as well as their lower ends, so that when standing side by side the ornamentation of adjacent loop-pipes extends toward the center of the length of the loop-pipes for different distances.

50 I claim—

The design for radiator herein shown and described.

In testimony whereof I have signed my name to this specification in the presence of 55 two subscribing witnesses.

JOHN R. REED.
